US0D1024322S

(12) **United States Design Patent** (10) Patent No.: **US D1,024,322 S**
Matsuoka et al. (45) Date of Patent: ** Apr. 23, 2024

(54) **CONNECTING MEMBER FOR ENDOSCOPE**

(71) Applicant: **OLYMPUS MEDICAL SYSTEMS CORP.**, Tokyo (JP)

(72) Inventors: **Yuya Matsuoka**, Tokyo (JP); **Yuya Hidaka**, Tokyo (JP)

(73) Assignee: **OLYMPUS MEDICAL SYSTEMS CORP.**, Tokyo (JP)

(**) Term: **15 Years**

(21) Appl. No.: **29/891,438**

(22) Filed: **May 5, 2023**

Related U.S. Application Data

(62) Division of application No. 29/796,482, filed on Jun. 24, 2021, now Pat. No. Des. 989,956.

(57) **CLAIM**

The ornamental design for a connecting member for endoscope, as shown and described.

DESCRIPTION

FIG. 1 is a top perspective view of a connecting member for endoscope, showing the new design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof; and,

FIG. 8 is a perspective view of the connecting member for endoscope showing a state of use thereof.

The broken lines depict parts of the connecting member for endoscope that form no part of the claimed design.

1 Claim, 8 Drawing Sheets
